UNITED STATES PATENT OFFICE.

JOHN B. SEAGO, OF PEE DEE, NORTH CAROLINA.

GAGE-COCK.

1,171,072.

Specification of Letters Patent.

Patented Feb. 8, 1916.

Application filed March 17, 1915. Serial No. 14,989.

To all whom it may concern:

Be it known that I, JOHN B. SEAGO, a citizen of the United States, residing at Pee Dee, in the county of Anson and State 5 of North Carolina, have invented certain new and useful Improvements in Gage-Cocks, of which the following is a specification, reference being had to the accompanying drawings.

10 This invention relates to certain improvements in gage cocks, and it is an object of the invention to provide a device of this general character having novel and improved means whereby the same will be automatically sealed in the event the outer 15 projected portion of the cock should be broken off.

It is also an object of my invention to provide a device of this character whereby 20 the upper valve seat may be readily reground during the period the coacting boiler is in operation.

The invention consists in the details of construction and in the combination and 25 arrangement of the several parts of my improved gage cock whereby certain important advantages are attained and the device is rendered simpler, less expensive and otherwise more convenient and advantageous 30 for use, all as will be hereinafter more fully set forth.

The novel features of the invention will be carefully defined in the appended claims.

In order that my invention may be the 35 better understood, I will now proceed to describe the same with reference to the accompanying drawings, wherein is disclosed a longitudinal sectional view taken through a gage cock constructed in accordance with 40 an embodiment of my invention, the coacting boiler being shown in fragment.

As disclosed in the accompanying drawings, 1 denotes a casing adapted to be threaded into a boiler B or the like and 45 having produced in the bore 2 thereof the reversely disposed valve seats 3 and 4, the innermost valve seat 3 having coacting therewith the safety valve 5 adapted to be engaged with its seat under the tension of 50 the pressure within the boiler. Coacting with the outer extremity of the casing 1 and detachably engaged therewith, preferably through the medium of a coupling 6, is a barrel 7 having its inner extremity provided with the inwardly disposed annular

flange 8, the periphery thereof being threaded and with which is adjustably engaged the elongated tubular valve member 9, the inner end 10 thereof being closed and adapted to coact with the valve seat 4, hereinbefore referred to, for a purpose which will hereinafter be more particularly set forth. Projecting from the end 10 at substantially the axial center thereof and longitudinally of the valve member 9 is the needle or finger 65 11 projecting within the recess or cavity 12 produced in the adjacent extremity of the safety valve 5 and serving to normally maintain said safety valve in an open adjustment. It will be readily perceived, however, that should the barrel 7 be broken off, the tension of the pressure within the boiler will cause the valve 5 to assume immediately a closed position.

The valve member 9 is of such a length 75 as to project beyond the outer extremity of the barrel 7 and to said projected portion is suitably affixed an operating member 14 whereby requisite movement may be imparted thereto to cause the same to either 80 engage the valve seat 4 or to be removed therefrom. Coacting with the projected extremity of the valve member 9 and the adjacent end portion of the barrel 7 is a conventional packing nut 15 whereby a steam tight 85 joint or connection is assured.

The outer extremity of the valve member 9 has secured thereto a packing nut 16 through which is threaded the elongated stem 17, the inner extremity whereof being adapted to coact with the valve seat 18 produced within the valve member 9 adjacent the inner end 10 thereof, said stem 17 being of a transverse diameter less than the corresponding diameter of the bore of the member 9 so that the fluid passing through the openings 19 disposed through the valve member 9 inwardly of the seat 18 thereof and through the additional openings 20 produced in said valve member 9 adjacent the 90 depending discharge nozzle 21 may have an unobstructed flow when the inner extremity of the stem 17 is adjusted away from the coacting valve seat 18. It is also to be understood that the bore 22 of the barrel 7 100 has a transverse diameter in excess of the corresponding diameter of the valve member 9.

In order that the stem 17 may have the 110 requisite longitudinal movement imparted

thereto, I suitably affix to the outer extremity thereof a conventional operating wheel or member 23.

It will be at once appreciated that the 5 valve seat 18 may be termed the principal valve seat, and in order that the same may be readily ground when the occasion requires without interfering with the operation of the boiler, it will be seen that it is only necessary to adjust the valve member 9 to operatively engage the coacting valve seat 4 whereupon flow through by improved gage cock is prevented and whereupon the stem 17 may be readily removed and a suitable 10 grinding implement disposed within the member 9 to operatively engage the valve seat 18 for the purpose of grinding the same. It will also be perceived that with the stem 17 withdrawn, its engaging or inner extremity may be also ground, as required. I also 15 find it of advantage to position within the bore 2 of the casing 1 adjacent the inner extremity thereof the perforate disk 24 which serves as a guide for the safety valve 20 5 and which also serves as a medium to prevent its displacement from within the bore 2, said safety valve, as herein disclosed, comprising an elongated shank having disposed at substantially its longitudinal center the 25 30 outwardly directed annular flange 25. I also find it in practice especially desirable to have the casing 1 formed into two separable sections 26 and 27 detachably engaged one with the other, as indicated at 28, in a conventional manner. It is to be observed that the section 26 of the casing is directly engaged with the boiler B and is provided with the valve seat 3, hereinbefore referred to, while the second or outer section 27 is 35 40 provided with the valve seat 4. In the event that the outer section 27 should be broken off, it will be perceived that in order to effectively repair the cock, it will only be necessary to replace this particular part.

45 From the foregoing description, it is thought to be obvious that a gage cock constructed in accordance with my invention is of an extremely simple and comparatively inexpensive nature and is particularly well 50 adapted for use by reason of the convenience and facility with which it may be assembled, and it will also be obvious that my invention is susceptible of some change and modification without material departure from the 55 principles and spirit thereof and for this reason I do not wish to be understood as limiting myself to the precise arrangement and formation of the several parts herein shown in carrying out my invention in 60 practice.

I claim:

1. A device of the character described comprising a casing adapted to be projected within a boiler and provided with an internal valve seat, a barrel engaged with the

outer extremity of the casing, an elongated tubular valve member disposed through the barrel and capable of longitudinal movement, the inner end of said valve member being closed and adapted to coact with the valve seat within the casing, said tubular valve member being provided with perforations communicating with the bore thereof, said valve member being also provided with an internal valve seat in close proximity to 75 its inner end and inwardly of certain of the perforations, and a stem projecting within the tubular valve member and capable of longitudinal movement adapted to coact with the internal valve seat of the valve member, the diameter of the stem being less than the diameter of the bore of the valve member and the diameter of the valve member being less than the diameter of the bore of the barrel, said barrel being provided 35 with a discharge opening.

2. A device of the character described comprising a casing adapted to be projected within a boiler and provided with an internal valve seat, a barrel engaged with the outer extremity of the casing, an elongated tubular valve member disposed through the barrel and capable of longitudinal movement, the inner end of said valve member being closed and adapted to coact with the valve seat within the casing, said tubular valve member being provided with perforations communicating with the bore thereof, said valve member being also provided with an internal valve seat in close proximity to 90 its inner end and inwardly of certain of the perforations, a stem projecting within the tubular valve member and capable of longitudinal movement adapted to coact with the internal valve seat of the valve member, the diameter of the stem being less than the diameter of the bore of the valve member and the diameter of the valve member being less than the diameter of the bore of the barrel, said barrel being provided with a discharge opening, and means for imparting longitudinal movement to the valve member.

3. A device of the character described comprising a casing adapted to be projected within a boiler and provided with an internal valve seat, a barrel engaged with the outer extremity of the casing, an elongated tubular valve member disposed through the barrel and capable of longitudinal movement, the inner end of said valve member being closed and adapted to coact with the valve seat within the casing, said tubular valve member being provided with perforations communicating with the bore thereof, said valve member being also provided with an internal valve seat in close proximity to 115 its inner end and inwardly of certain of the perforations, a stem projecting within the tubular valve member and capable of longitudinal movement adapted to coact with the internal valve seat of the valve member, the diameter of the stem being less than the diameter of the bore of the valve member and the diameter of the valve member being less than the diameter of the bore of the barrel, said barrel being provided with a discharge opening, and means for imparting longitudinal movement to the valve member.

- internal valve seat of the valve member, the diameter of the stem being less than the diameter of the bore of the valve member and the diameter of the valve member being 5 less than the diameter of the bore of the barrel, said barrel being provided with a discharge opening, said casing being provided with a second internal valve seat, a safety valve within the casing adapted to coact 10 with the second valve seat, and means carried by the inner extremity of the valve member for maintaining said safety valve in open adjustment.
4. A device of the character described 15 comprising a casing adapted to be projected within a boiler and provided with an internal valve seat, a barrel engaged with the outer extremity of the casing, an elongated tubular valve member disposed through the 20 barrel and capable of longitudinal movement, the inner end of said valve member being closed and adapted to coact with the valve seat within the casing, said tubular valve member being provided with perforations 25 communicating with the bore thereof, said valve member being also provided with an internal valve seat in close proximity to its inner end and inwardly of certain of the perforations, a stem projecting within the tubular valve member and capable of longitudinal movement adapted to coact with the internal valve seat of the valve member, the diameter of the stem being less than the diameter of the bore of the valve member and the diameter of the valve member being 30 less than the diameter of the bore of the barrel, said barrel being provided with a discharge opening, said casing being provided with a second internal valve seat, a safety valve within the casing adapted to coact 35 with the second valve seat, means carried by the inner extremity of the valve member for maintaining said safety valve in open adjustment, and means within the casing 40 coacting with the safety valve for maintaining the same against displacement.

In testimony whereof I hereunto affix my signature in the presence of two witnesses.

JOHN B. SEAGO.
